UNITED STATES PATENT OFFICE

2,427,051

EXTENSION LIGHT FOR FLASHLIGHTS

Henry A. Goudreau, Lynn, Mass.

Application September 12, 1945, Serial No. 615,759

1 Claim. (Cl. 240—2.18)

1

The present invention relates to new and useful improvements in flashlights, and more particularly to an extension carried by the flashlight and by means of which a light may be projected directly upon inaccessible parts of machinery or into restricted places.

An important object of the invention is to provide a flexible lamp cable embodying means for connecting the inner end thereof to the batteries of a conventional form of flashlight and under the control of a switch carried by the flashlight for energizing the extension lamp either simultaneously with the lamp of the flashlight or independently thereof.

A further object of the invention is to provide an extension lamp for flashlights constructed as a unitary part of the flashlight.

A further object is to provide a device of this character of simple and practical construction, which is efficient and reliable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like reference numerals refer to like parts throughout, and in which:

Figure 1 is a side elevational view with parts broken away and shown in section,

Figure 2 is a view in elevation of the extension cord removed from the flashlight,

Figure 3 is a perspective view of the contact between the batteries of the flashlight and the main flashlight lamp and forming the connection for the extension lamp, and

Figure 4 is a rear elevational view of the flashlight.

Referring now to the drawing in detail, wherein, for the purpose of illustration, I have disclosed a preferred embodiment of the invention, the numeral 5 designates the tubular flashlight casing having the batteries 6 mounted therein in the usual manner, the front end of the casing having the reflector 7 mounted therein and in which the main flashlight lamp 8 is supported. The base of the lamp 8 is electrically connected with the contact 9 at the front end of the battery by means of a contact 10 projecting through opposite sides of an insulation disk 11 secured in the front end of the casing.

A housing 12 is formed at one side of the casing 5 at its front end and in which is secured a tubular shell 13 having its rear end closed as

2

indicated at 14 and its front end open at the open front end of the housing 12 and in which a cylindrical plug 15 is removably inserted, the plug having a flexible metal cable 16 extending from the front end thereof.

The outer end of the cable 16 is formed with a lamp socket 17 within which a flashlight lamp 18 is mounted, the base of the lamp having contact with the outer end of an insulated electric cable 19 extending through the cable 16 and into the plug 15.

The inner end of the cable 19 is connected to a plug 20 having a rounded head 21, the plug 20 being secured to the rear end of the plug 15 and insulated therefrom by means of the washers 22.

The rounded head 21 of the plug 20 is adapted for detachable engagement with a spring clip 23 secured to the inside of the rear wall 14 of the shell 13. A pin 24 is connected to the clip 23 and extends through the rear end 14 of the shell 13 and is insulated therefrom, and to the rear end of the pin is connected one end of an electric wire 25 extending through an opening 26 in the casing 5 and connected to the rear end of the contact 10.

The battery casing 5 is provided with a conventional form of switch 27, which may be of a two-way type for controlling the energization of the main bulb 8 of the flashlight, or the extension bulb 18, so as to selectively energize either the bulb 8 or the bulb 18.

The switch includes a swinging contact 28 connected to the battery casing 5 and having its free end adapted for selectively engaging contacts 29 or 30. The contact 29 has a wire 31 leading to a leaf spring 32 with its free end projecting through an opening 33 in the shell 13 to contact the plug 15. The other contact 30 has a wire 34 leading to the reflector 7.

40 The circuit for the bulb or lamp 18 is through the contact 10, wire 25, pin 24, clip 23, plug 20, to the cable 19 and then to the lamp 18, the lamp being grounded through the socket 17, flexible cable 16, plug 15, spring 32 and wire 31 to the contact 29 and casing 5.

The flexible cable 16 may be of any desired length and accordingly the lamp 18 of the extension may be placed into inaccessible positions for directly illuminating inaccessible parts of machinery which otherwise could not be effectively illuminated by the main bulb 8 of the flashlight.

In view of the foregoing description taken in conjunction with the accompanying drawings, it is believed that a clear understanding of the construction, operation and advantages of the device

will be quite apparent to those skilled in this art. A more detailed description is accordingly deemed unnecessary.

It is to be understood, however, that even though I have herein shown and described a preferred embodiment of my invention that the same is susceptible to certain changes fully comprehended by the spirit of the invention as herein described and the scope of the appended claim.

Having thus described the invention, what I claim as new is:

A flashlight including a case having a battery therein and a lamp electrically connected to the battery, a housing at one side of the case, a shell in the housing, a spring clip in the shell and electrically connected to the battery, an extension lamp, and a plug at one end of the extension lamp slidably received in said shell for frictional engagement therewith, and a contact on the inner end of the plug for detachable connection with the clip. 20
